UNITED STATES PATENT OFFICE.

GREENLEAF WHITTIER PICKARD, OF AMESBURY, MASSACHUSETTS, ASSIGNOR TO
WIRELESS SPECIALTY APPARATUS COMPANY, OF NEW YORK, N. Y., A CORPORATION OF NEW YORK.

CONSTANT-PRESSURE SOLID RECTIFIER.

1,257,526.

Specification of Letters Patent. Patented Feb. 26, 1918.

Application filed September 15, 1908. Serial No. 517,771.

To all whom it may concern:

Be it known that I, GREENLEAF WHITTIER PICKARD, a citizen of the United States of America, and a resident of Amesbury, Mass., have invented certain new and useful Improvements in Constant-Pressure Solid Rectifiers, the principles of which are set forth in the following specification and accompanying drawing, which disclose the form of the invention which I now consider to be the best of the various forms in which the principles of the invention may be embodied.

This invention relates to improvements in solid rectifiers of oscillating and alternating currents of electricity, having utility particularly with small currents, such for example, as those employed in radio telegraphy and telephony. The object of the invention is to increase the efficiency of solid rectifiers, with particular respect to use as oscillation receivers in radio telegraphy or telephony, wherein the currents are extremely minute.

The invention consists chiefly, among other things, of the constant pressure solid rectifier hereinafter claimed, and described in connection with the accompanying drawings which are full scale and of which Figure 1 is a front elevation of a complete device constituting one of the many possible embodiments of the invention; Fig. 2, a plan of the same; Fig. 3, an end elevation; Fig. 4, a transverse section of the sliding sur-base 1; Fig. 5, a plan and transverse section of contact-point carrier 8; Fig. 6, side and front elevations of counterweight 12; Fig. 7, side and front elevations of a heavy weight 14, and Fig. 8, side and front elevations of a light weight 13.

Most of the solid rectifying substances are commercially operative only on a fracture or cleavage surface, which is almost invariably uneven, as distinguished from a flat or even surface, obtained as by grinding or polishing. Even where portions of a fracture face are smooth, the surface receiving the circuit-making conductor is uneven as a whole. Heretofore the two conductors, the rectifier and the circuit maker, (or two rectifying conductors) have been pressed together, to obtain the substantially perfect

and minute contact necessary to effectuate the rectifying property, by means of a spring; the chief difference in the structure of the conductor-holder, from prior oscillation receivers or detectors of the microphonic or coherer type, being the employment of greater pressure for a given material sufficient to convert the contact from a microphonic or imperfect contact not permitting operation by oscillation-rectification or valve-action, into the kind of contact above-specified as necessary for such operation.

The spring-action, entirely suitable for delicate adjustments to imperfection of contact, has been considered heretofore as entirely satisfactory for solid rectifiers, when so essentially and vitally modified as above as to permit rectifying action, and it has been assumed that it permitted optimum efficiency of the rectification properties of the respective rectifying solids. I have discovered, however, that by the means substantially as disclosed herein, the rectifying efficiency of practically all solid rectifiers can be materially increased, not only as to the ease of adjustment of the minute good contact, but as to the actual apparent rectifying property of the material. This result seems to be due to the ability of the means which co-operates with the rectifying material, to bring out and utilize to the maximum the inherent property of said material as it never has been before by means of the various forms of spring contact.

As a result of this invention the actual but previously hidden defects of the spring-contact method of obtaining the good contact required for rectifying action, are now made apparent. In practice, adjustment must be made very quickly on account of the exigencies of the rapid telegraphy customary with the present advanced state of the art, and the result is that, with the various points of the rectifying material which are employed, and the various degrees of spring pressure, the same pressure is practically never used on a given place of contact, and almost never, in practice, is the optimum pressure employed. Furthermore, an adjustment to optimum pressure (meaning here pressure for optimum efficiency) at

a given contact will probably not be the optimum pressure for any other contact of a different elevation on the uneven surface of the rectifying material. It follows that for 5 a given adjustment there will be only a few surface contact points of high rectifying efficiency, and for another given adjustment there will be only a few other such contact points, the result being that at no one time, 10 and probably never, will an operator in practice have a large number of efficient contacts from which to rapidly select in the rush of commercial business. A further and most important defect of the spring operated contact is that for a given adjustment the operator seldom, if ever, can use a contact of maximum efficiency.

As a result of this invention, nearly all 20 rectifying materials tested by me have a much higher apparent maximum efficiency and a much larger maximum number of surface contact points, of approximately maximum efficiency, and can be adjusted with far greater rapidity, than in the case of the 25 employment of a spring contact. The means for accomplishing this result is of such nature that, a careful determination of the good contact pressure producing maximum efficiency having been once obtained for a 30 given quality of a given rectifying material, that pressure is maintained constant for that material of that quality, and is never varied by the operator, although he is free to select any desired point of contact on the material. 35 And this means for revolutionizing this art of the good contact rectifying detector consists simply in substituting the action of gravity for the contact spring heretofore employed. That is to say, the difference in 40 effect between the action of the spring and the action of gravity, in a good contact rectifying device, is the measure of the novelty of the broad invention, in that the spring necessarily causes a variation in pressure, by 45 expansion or compression, for contact points of varying elevations, while the gravity, of a given mass, permits movement of the co-operating contact over the uneven surface of the rectifying conductor but always limits 50 the contact pressure to the amount determined by the adjustment or mass of the weight, no more and no less. Therefore the optimum pressure for one contact point is the optimum pressure for all contact points, 55 and since that pressure is permanently predetermined in advance of use by the operator, it is always certain that the pressure used is the pressure which is optimum for the particular rectifying material employed. 60 The net result, in practice, is that a much higher sensitiveness or efficiency of rectification than heretofore is constantly maintained, an entire new field is opened up on the rough or uneven surface of the material, 65 and rich in an infinity of contact points of opti-

mum efficiency, and the operative adjustment to any contact point is instantaneous, so that if necessary the contact may be changed in the midst of the reception of a message, in case of the previous contact becoming temporarily inoperative for any reason.

In brief, the invention in its broadest aspect comprises a contact operating by gravity to obtain good or substantially perfect 75 electrical contact on the surface of a material possessing the property of rectification under the conditions now well known as the result of my investigations. The invention does not include microphonic contact detectors of any kind and has no relation with 80 such devices.

While the invention is so simple that it is readily understood without a drawing, yet the drawings are appended to show the best 85 form of device which I have so far used, the particular disclosed device being adapted not only for commercial use, but for accurate measurement work, and being less simple in construction than a device adapted wholly 90 for commercial work. The rectifying conductor galena is particularly specified herein as one of the most marked cases of improvement by this invention. While I have found galena to have a high power of rectification, yet it is impracticable as a commercial device for use in present day service, with the prior spring or variable pressure contact, on account of its low degree of stability and its great difficulty of adjustment, 100 that is to say, a given contact point on the surface is liable to become inoperative, and a new adjustment requires a time so long as to be out of the question for commercial business. But by means of the constant pressure contact of this invention, the number of operative contact points is so greatly increased, that considering its high rectification power, the disadvantageous feature of 105 instability of contact is more than offset. 110

The efficiency of the gravity contact is so great that in cases of some solid rectifiers, the efficiency of rectification is thereby increased even slightly in excess of that of 115 oxid of zinc of my prior Patent No. 924,827 of June 15th, 1909.

Any of the solid rectifiers having the customary uneven surface X, may be held in the metal cup C, Fig. 4 as by fusible metal F. (If desired, any of said solid rectifiers may be employed in the device of my said Patent No. 924,827 of June 15th, 1909.) The shank of this cup is removably held in brass part 1, Fig. 4, by screw 2. Hard rubber part 3, Figs. 4 and 1, contains brass part 1, and 120 binding post 4, Figs. 4 and 1, extends through 3 into 1 to connect the solid rectifier in cup C with one side of the circuit. All the above apparatus rests on marble base B, Fig. 1, but is not attached to the base, 125

being left free to be moved around under the gravity contact point. Base B is provided with soft rubber feet 5. The gravity contact point is carried at the right hand end of 5 the aluminum beam or balance lever L mounted on brass standard S, Fig. 1, so as to be forced by gravity down on the uneven surface X. The second binding post for the other side of the circuit is at 6 in standard 10 and S, Fig. 1.

This balance device is not by any means the only possible embodiment of the invention, nor, indeed, need the gravity contact be rigidly mounted, because the substantial 15 benefits of the invention would be present even if the gravity contact were carried by a spring so light and elastic as not to prevent the effective action of the weight in permitting substantially constant contact pressure. 20

In this disclosure balance lever L has secured to it a brass pin 7, Fig. 1, over which is slipped a brass holder 8, Fig. 5, for brass contact-point P. Any desired conducting 25 material may be used for P, such as any of the solid rectifiers, as boronite. Screws 10, 11 hold 8 to 7, and P to 8 respectively.

Balance lever L has a knife-edge mounting on standard S, as shown. In this particular case the gravity effect is obtained by the lever and its appurtenances including 7, 8, P, 10 and 11, but in substance the device is simply a gravity-acting contact. In the case disclosed a brass counterweight 12, 35 Figs. 6 and 1, is provided, this being about twice the weight of the point-holder 8, Fig. 5. In order that the device may be operated with various samples of each of various rectifying solids, as for purposes of measurement, etc., an adjustment is provided, consisting of varying weights 13, 14, Figs. 1, 6, 7 and 8, operating on lever L along the graduated scale which extends from the knife-edge support to the center of pin 7. Weights 13 45 and 14 may be of 1 gram of aluminum and 10 grams of brass respectively.

A conducting lead 15, Fig. 1, preferably connects L and S in shunt to the knife-edge support, to insure good circuit connections. 50 This lead 15 should be of fine copper wire to have minimum resilience.

Under the left end of beam L a brass standard 16 may be secured to base B, and provided with an adjusting screw 17.

55 In devices intended exclusively for commercial use by telegraph operators it is recommended that no weight adjustment be permitted, provided that the operators are furnished with cups C containing a given solid rectifier of constant quality. The device should be then set to the pressure determined in the laboratory by a control instrument such as illustrated herewith, to be optimum for that standard material.

60 A great advantage of the invention is

that there is practically no adjustment to the device. It is always ready when X is under contact point P with the proper predetermined pressure. Normally there is nothing for the operator to do. In case his testing 70 buzzer ever shows that the device has for some reason become inoperative as to the particular surface point of X in contact with P, it is permissible for him to move holder 3 slightly to obtain a new surface contact 75 point. That, however, will very seldom be required in case of proper selection of rectifying material and proper predetermination of contact pressure. But when it does occur, as it may in the midst of a message, it is essential 80 that the operator be able to instantly restore complete operativeness; and that is certainly permitted in all cases for the first time by this invention, by reason of the fact that the contact pressure is automatically 85 maintained constant irrespective of the movements of holder 3 and of the consequent varying elevations of X thereby caused to engage with contact point P; all as more particularly pointed out hereinbefore. 90

I claim:

1. The combination with a solid rectifier of the class described and a contact member therefor, said members being relatively adjustable in respect of making contact with each other at various points of the contact-surface of the rectifier, of means carrying one of said members and movably mounted on a bearing which permits the mass of said means and contact-member to exercise exclusive control of the contact-pressure between the two contact-members. 100

2. The combination with a solid rectifier of the class described, of a contact member co-operating therewith, said members being adjustable to various points of contact on the surface of the rectifier, and means for pivotally supporting one of said contact-members whereby it is free to be pressed against the other contact member exclusively by means of the weight of its support and of itself. 105

3. The combination with a mass of rectifying material having an uneven operating contact surface, of a contact member co-operating therewith, means for changing the location of the rectifying material to bring different parts of its surface into contact with the contact member, and means for movably supporting the contact member 115 whereby it is free to be pressed exclusively by the weight of its support and of itself into a contact of operative pressure with the rectifying material. 120

4. The combination with a mass of rectifying material of the class described and having an uneven operating contact surface, of a contact member co-operating therewith, and means for freely supporting said contact member near the rectifying material 130

whereby its contact-pressure therewith is controlled exclusively by the action of gravity.

5. The combination with a mass of rectifying material of the class described and having an uneven operating contact surface, of a coöperating contact a means for holding the latter in operative contact with the uneven operating contact surface exclusively 10 by the action of gravity.

6. The combination with a mass of rectifying material of the class described, of a contact member coöperating therewith, said rectifying member having an uneven contact surface, and the rectifying member and contact member being relatively movable for the selection of various contact points on the surface of the former; and means controlled exclusively by gravity for obtaining uniform contact-pressure between the contact 20

member and the various contact points on the uneven contact surface of the rectifying material.

7. In a device of the character described, a base or support, a contact disk mounted 25 upon said support, a contact cup provided with an uneven contact surface rotarily mounted on said disk and an oscillatory weighted beam bearing a member coöperating therewith. 30

8. In a device of the character described, means for supporting a pair of coöperating contacts, one of said contacts having an uneven operating surface and one of said contacts controlled by a weighted beam.
